RADIO RECEIVER

Sakae Nakamoto, Kobe, and Masanori Hamada, Osaka, Japan, assignors to Matsushita Electric Industrial Co., Ltd., Kadoma, Osaka, Japan

Filed May 6, 1970, Ser. No. 22,860

Claims priority, application Japan Nov. 7, 1969

Term of patent 14 years

Int. Cl. D14—03

U.S. Cl. D56—4

FIG. 1

FIG. 2

FIG. 3

FIG. 4

FIG. 5

FIG. 1 is a left side, top and front perspective view of a radio receiver, showing our new design;

FIG. 2 is a right side, top and rear perspective view with the antenna in folded position;

FIG. 3 is a right side elevational view with the antenna in extended position;

FIG. 4 is a top plan view; and

FIG. 5 is a bottom plan view thereof.

Portions of the drawing figures are shaded to indicate contrast in appearance, and portions are diagonally lined to indicate transparency.

We claim:

The ornamental design for a radio receiver, as shown and described.
